UNITED STATES PATENT OFFICE.

CHARLES ROBERT ARCUS, OF RAMSGATE, ENGLAND, ASSIGNOR TO CLAXTON AND COMPANY LIMITED, OF RAMSGATE, ENGLAND.

SCALE REMOVER FOR TUBES.

Application filed December 2, 1926, Serial No. 152,234, and in Great Britain December 10, 1925.

This invention relates to improved means for removing scale from boiler tubes and the like and has for its object to enable an efficient method of removing scale from the tubes to be put into practice by means of simple apparatus adapted to be traversed through the tubes so as to apply heat thereto locally in such a manner that the heated scale on the tube will dry and crack off in loose particles, which may be readily removed.

Heretofore it has been proposed to provide heating means adapted to be passed along the tubes and to be traversed along their length in such a manner that the heat will be applied locally to the tube as the device is traversed along the length thereof. For this purpose, the heating means heretofore proposed comprises in one instance an oxygen burner, and in another instance a burner to which pipes are connected, one of which conveys air or oxygen and the others conveying acetylene or oil vapour to a common mixing chamber. The combustion takes place inside the boiler tube itself, but as the carbon or incrustation is a very poor conductor of heat, the metal boiler tube is liable to get excessively heated. In one heretofore proposed device, it is proposed to obviate this by directing a cooling liquid from the burner into the boiler tube subsequent to each heating operation. According to my invention the combustion of the fuel does not take place inside the boiler tube itself, but inside a shell which is fed along the interior of the boiler tube, the shell having openings to allow flames to issue from the shell and spread around the interior of the boiler tube.

In carrying my invention into practice, I prefer to employ a burner mounted upon the end of a suitable shaft as heretofore proposed, the shaft being of a sufficient length to enable the burner to be traversed throughout the whole length of the tubes to be treated.

A convenient construction of burner for use with liquid fuel comprises a suitable head in the form of a cylindrical metal casting mounted upon the end of the shaft to which it may be screwed or otherwise conveniently attached. The shaft is solid and there is a pipe for the fuel parallel with it

which is led through holes drilled or otherwise formed in the burner head to one end of a vaporizing coil. This coil may conveniently consist of a suitable length of pipe or casting of any suitable metal, one end of which is attached to the hole leading to the fuel supply passage in the hollow shaft. The other end is secured to the burner head and leads into a passage communicating with a central nozzle at the end of the head so arranged as to direct the vapourized fuel toward the vaporizing coil. The fuel issuing from the nozzle is ignited in the usual way so that the flame will maintain the vaporizing coil at a suitable temperature to ensure sufficient vaporization of the fuel. The flame from the burner is directed or deflected outwardly toward the sides of the boiler or other tube into which the device is inserted so as to play upon the interior of the tube and effectively heat it so as to cause any scale thereon to dry up and crack off in loose particles as the burner is traversed along the length of the tube. A suitable casing of tubular or other desired form may be mounted round the burner head and the vaporizing coil and a suitable outlet and deflector may be arranged upon the end of this casing so as to direct the flame outwardly against the surface of the tubes in which the device is used. For this purpose, an end plate may be provided on the casing formed with curved or inclined vanes or deflectors adapted to impart swirling motion to the gases to assist in mixing the vaporized fuel and air and to direct the burning mixture outwardly against the surface of the tube under treatment.

Suitable apertures may be provided through the burner head to permit an ample supply of air to ensure correct combustion. For this purpose the burner head may be formed with an apertured flange or a number of radial arms connected to the sides of the tubular casing thus leaving ample openings for the passage of air to the burner. The tubular casing on the burner is arranged to be a loose easy fit in the tubes under treatment and thus acts as a guide in passing it through the tubes.

In order that this invention may be clearly understood and readily carried into effect, I have appended hereto a sheet of drawings

illustrating an embodiment of same, and wherein:—

Fig. 1 is a sectional elevation of the device.

5 Fig. 2 is a plan view of Fig. 1, and
Fig. 3 is an inverted plan view of Fig. 1.

Referring to the drawings, the device illustrated comprises a burner *a* mounted upon the end of a shaft *b*. The shaft *b* is sufficiently long to enable the burner to be traversed along the length of a boiler tube, and for this purpose the shaft *b* may be constituted by a number of rods or shafts 10 detachably connected in series end on end.

15 The burner *a* is in the form of a part cylindrical head having a passage *c* for liquid fuel, such passage *c* having connected to one end of it a tube *d* connected to a source of liquid fuel supply by a pipe *e* which runs 20 parallel with the shaft *b*, and the shaft *b* employed for conveying liquid fuel to the tube *d*. The other end of the passage *c* communicates with a jet *f* preferably disposed upon the axis of a cylindrical casing *g*, accommodating the burner *a* and the tube *d*. The tube *d* preferably is formed with a coil *h* located across the path of the flame issuing from the jet *f*, whereby the liquid fuel in the tube *d* can become atomized or 25 vaporized.

30 The casing *g* is a cylindrical metal shell open at its inner end or base *i*, but provided with a cap *j* at its outer or upper end. The cap *j* is provided with openings for the emission of the burning combustible mixture, and these openings are preferably arranged so 35 that the flame and hot gases issue in a spreading or fan-like manner from the cap *j*. This can be effected by making the said openings in the form of a number of substantially radiating slots *k*, the intermediate blades *l* each being flared outwards, so that one radial edge is above the other radial edge, the inner ends of the blades being turned in a 40 substantially tangential direction. By this means the issuing flames and hot gases will tend to travel in a spiral-like manner along the tube being treated.

45 The shaft *b* is provided with an aperture 50 flange and number of radial arms *m* the periphery or outer ends of which is, or are, secured to the shell *g*. If desired one side of the shell *g* may be formed with an opening as indicated at *n*, or a number of openings 55 may be provided. The outer or upper end of the shell *g* is also preferably provided with a number of openings *o* through which flames deflected by the coil *h* may pass and impinge radially upon the boiler tube.

60 The operation of cleaning boiler tubes according to my invention is carried out with the boiler empty. The device is passed slowly along the length of each tube in turn so that the tube is subjected to a sufficiently 65 high temperature to heat the scale on the

tube causing it to crack off in flakes which will fall to the bottom of the boiler and may be easily removed through the usual man-hole or sludge outlets. The local application of heat to the tube causes it to expand 70 and contract as the device is passed along it, thus assisting in breaking away the scale. The heating of the tube in this manner is beneficial as it has an annealing effect upon the metal. The removal of the scale from 75 the tubes of boilers and the like in the manner described may be carried out quickly and at small cost and without the necessity for dismantling the boiler. It is much more efficient than the usual method of scraping off 80 the scale from between the tubes and enables the whole of the scale to be removed, thus promoting economy of fuel and ensuring greater efficiency of the boiler in use. When it is desired to withdraw tubes from the 85 boiler, this can be greatly facilitated by first removing scale in the manner described.

I claim:—

1. A scale remover for boiler tubes comprising a cylindrical shell immovably fixed on an axial manipulating shaft which extends into the shell from the rear end thereof, a fixed head on the inner end of said shaft, a burner on said fixed head, a fuel conveying pipe to said burner which extends 90 alongside and parallel with the shaft, and a front end wall to the shell having a plurality of apertures to divide the flame emerging from the burner into a number of separate flame tongues. 100

2. A scale remover for boiler tubes comprising in combination, a liquid fuel burner, a cylindrical shell in which said burner is housed, having a front end face in a plane perpendicular to the axis of said shell, a 105 number of openings in such end face radial with respect to the axis of the shell to divide flame emerging from the burner into a number of separate tongues of flame, a fixed manipulating shaft extending into the shell 110 from its rear end, having a fixed head at its inner end in which the burner is mounted, and a liquid fuel conveying pipe disposed alongside the shaft, parallel therewith, and having an extension located within the shell 115 between the burner and the front end of the shell, and connected to a liquid fuel passage in the shaft head.

3. A scale remover for boiler tubes comprising in combination a liquid fuel burner, 120 a shell in which said burner is housed, having a front end face in a plane perpendicular to the axis of said shell, a number of openings in such end face, and outwardly flared blades between the said openings to 125 spread in spiral fashion tongues of flame which emerge from the openings.

4. A scale remover for boiler tubes comprising in combination, a liquid fuel burner, a shell in which said burner is housed, hav- 130

ing a front end face in a plane perpendicular to the axis of said shell, a number of openings in such end face radial with respect to the axis of the shell to divide flame 5 emerging from the burner into a number of separate tongues of flame, outwardly flared blades between the said radial openings to direct such flame tongues in spiral fashion, a fixed manipulating shaft extending into the 10 shell from its rear end, having a fixed head at its inner end in which the burner is mount- ed, a liquid fuel conveying pipe disposed alongside the shaft, parallel therewith, and having an extension located within the shell between the burner and the front end of the 15 shell and connected to a liquid fuel passage in the shaft head, and an apertured flange positioned between the shaft head and the rear end of the shell, by which the shell is secured to the shaft.

CHARLES ROBERT ARCUS.
